CLAIM

The ornamental design for an intraoral oximeter sensor, as shown and described.

DESCRIPTION

FIG. 1 is a bottom perspective view of an intraoral oximeter sensor showing our new design;

FIG. 2 is a bottom plan view thereof;

FIG. 3 is a top plan view thereof;

FIG. 4 is a right side view thereof;

FIG. 5 is a left side view thereof;

FIG. 6 is a front view thereof; and,

FIG. 7 is a rear view thereof.

The broken-line features in the figures are for illustrative purposes only and form no part of the claimed design.
